DETACHING MEANS FOR ABRASIVE DISKS

Arthur Turton and Henry Elbert Hickman,
Los Angeles, Calif.

Application April 2, 1951, Serial No. 218,819

2 Claims. (Cl. 51—197)

1

As the title indicates the present invention concerns abrasive discs and in particular with means to attach and detach such discs upon the driven arbor of a manually manipulated motor for use in grinding, buffing and polishing sheet metal, particularly the sheet metal work of automobiles and the like.

Automobile sheet metal repair and paint shops find it necessary to use a succession of abrasive discs upon a single job, which discs are specialized for particular operations, that is, some discs are formed with coarse abrasive material for fast cutting or roughing in, while others are formed with different degrees of fineness of abrasive material for finishing work. On the job there is a natural sequence in the selection of the discs to be used, which is primarily determined by the condition of the work and the degree of smoothness to be given thereto, and such selection generally runs from the coarse, to the medium and then to the fine.

Abrasive discs for this type of work are centered upon a head attached to the motor shaft and are held compressed between such head and a flexible disc stiffener thereon and a relatively large flat-headed nut threadedly attached thereto, thus to change from one disc to another requires the use of a wrench to hold the head against torque applied to the nut by the use of a second wrench.

It will thus be seen that the change discs in the presently customary manner is slow and cumbersome in such degree as to cause many workmen to attempt to finish a surface with a disc which is not adapted by its fineness to the finish required merely in an attempt to obtain greater output of volume of work so that in many cases the surface being worked is needlessly scored so that re-working thereof is required or the use of filling materials prior to painting must be resorted to, neither of which operations are or can be justified in the first instance, but which do represent a condition currently present in many shops, and in other instances a workman because of loss of time in conventionally changing from a fine to a coarser disc will undertake to use a fine disc upon a painted surface whereby under frictionally generated heat the paint will completely foul the sanding disc to the complete ruin thereof whereby needless expense and further loss of time are incurred.

Accordingly and in view of this condition it is a prime object of the invention to provide a novel, yet simple method for pyramided positioning of sanding discs upon a rotatable support head and

for the facile change over from one to another for functional use thereof.

Another object of the invention resides in the novel construction and combination of flat-headed disc support fittings so arranged with respect to one another as to be operable to release said disc without tools and whereby said disc may be held compressed therebetween and against a backing disc for functional use, the said sanding disc being releasable from between the fittings upon and by counter-rotation thereof with respect to another disc held between one of the fittings and a rotatable support head on the driving motor.

A further object of the invention resides in novel provision of tongue and slot means to releasably couple clamping elements whereby one element thereof having a sanding disc centered thereon is held under spring pressure to releasably clamp said disc for use.

Other objects, features and advantages of the invention may be noted from a study of the drawing, the detailed description thereof and the subjoined claims.

In the drawing:

Figure 1 is a top-plan view showing abrasive or sanding discs mounted for functional use within the purview of this invention.

Figure 2 is a side-elevational view showing the abrasive discs illustrated in Figure 1 and also showing in dotted lines the manner in which the discs are manipulated for quick change of the upper most one thereof, that is, the lower disc is bent slightly downward for hand grasp holding while the upper disc is slightly sprung or bent upwardly and is then manually rotated in a direction counter to the running of the threads as indicated by the arrow.

Figure 3 is a transverse sectional view through a disc and the screw fitting related in use thereto, the view also showing a small annular groove under the head of the fitting within which the disc is supported prior to assembly as shown in Figure 2; and,

Figure 4 is a similar type illustration excepting that here the disc is associated with a fitting adapted to threadedly receive the nut or fitting shown in Figure 3 and is itself adapted to be threadedly received in the rotatable head shown in Figure 2 for mounting upon the shaft of a motor.

Figure 5 is a transverse view of the head upon which all of the fittings and discs are mounted for functional use; and,

Figure 6 is a vertically transverse view showing

2

in section the whole of the assembly comprising this invention; while,

Figure 7 is a transverse sectional view taken substantially along line 7-7, Figure 6, to show the relative position of the fittings used to support the disc when assembled.

In Figures 8 through 16 we show another form of mounting sanding disc upon an arbor wherein the essential feature resides in the ease and general facility with which these discs may be 10 changed for specialized use; and wherein,

Figure 8 is a top-plan view of the assembled discs generally related and similar in appearance to the illustration shown in Figure 1.

Figure 9 is a side-elevation showing the assembled discs in their relation to the motor driving means.

Figure 10 is a view showing the disc support head in transverse section and showing the disc clamping means in side-elevation excepting that a portion of the first or primary fitting is broken away to facilitate illustration of the slot through which the secondary fitting is withdrawn for release of the upper-most disc.

Figure 11 is a side-elevational view of the secondary fitting; and,

Figure 12 is a similar view of the primary fitting.

Figure 13 is in general a transverse sectional view showing all of the parts of the assembly.

Figure 14 is a transverse sectional view taken along line 14-14, in Figure 10 showing the slot and bayonet relationship between the primary and secondary fittings.

Figure 15 is a top-plan view of the secondary fitting as seen along line 15-15, Figure 12, the view is generally intended to show the slot therein through which the pin or bayonet in the primary fitting is withdrawn for release of the primary fitting; and,

Figure 16 is a mid-vertical transverse sectional view thereof.

Figure 17 is a view in mid-vertical section showing the primary fitting and the rotatable head in socketed union and wherein these two structural elements of the invention are both screw threaded upon the driving shaft of the motor whereby they are held in unitary relationship.

In the drawing the reference character 1 indicates a plurality of abrasive discs 2 and 3 of which for the purpose of this description, disc 2 will be considered as being finer than the disc 3, that is, the grit or abrasive material forming the work surface thereof is finer or smaller than that of the other disc. The construction of these discs and the nature of the abrasive material thereon is quite immaterial to this invention for the reason that they are conventional items available to the trade, and all such discs are formed with a central opening for positioning upon an arbor or other centering support which in the present instance comprises a rotatable head 4 which is mounted upon the shaft 5 of a motor 6, a fragment only of which is shown in Figure 2.

The disc supporting head 4 is annular in transverse section for static balance and is formed with a cylindrical portion 6 having an annular flange 7 formed with a concaved top surface 7a upon which the discs 2 and 3 and a semi-resilient non-abrasive support disc or backing are positioned as shown in Figures 2 and 6. The support disc 8 may be formed of Micarta, stiff rubber or other equivalent material which is semi-

flexible for the reason that its primary duty is to provide a backing for the discs 2 and 3 whereby these working discs may be forced into yielding contact with the surface of the sheet metal being worked.

The medial vertical center of the head 4 is bored at 4a therethrough and this bore is threaded at 9 in the lower end thereof to receive the shaft 5 of the motor 6, and is tapped with fast running threads 10 in the upper end portion to receive like formed threads 10a upon the lower exterior body of the primary fitting 11.

The primary fitting 11 is formed with a body 12 having the aforementioned fast running threads 10a and with a concaved flange 13 the lower surface 14 of which is disposed at an angle substantially parallel with the degree of angularity of the concaved upper surface of the head 4 whereby upon assembly of the unit as shown in Figure 6, the flange surface 14 and the flange surface 1a constitute pressure surfaces to firmly secure the sanding discs 3 and the resilient backing disc 8 in functional use position. The upper surface 15 of the flange 13 lies substantially parallel with the lower surface 14 thereof. A small annular groove 16 is cut in the outer wall of the part 12 adjacent to and under the flange 13 to form a seat or point to engage the wall of the opening common to all discs of the character herein contemplated for use. In practice the body 12 of the fitting 11 is inserted and centered in the opening in the disc as shown in Figure 4 so that thereafter the disc can be forced into the groove 16 as shown 35 for temporary retention of the disc upon the fitting.

The primary fitting 11 is bored medially and longitudinally of its length and is tapped with course or fast running threads 17 to receive like 40 formed threads 17a upon the body 18 of the secondary fitting 19 as illustrated in Figure 3, wherein it will be noted that this fitting is also provided with an annular flange 20 the under 45 surface of which is angularly aligned with the flange 15 on the primary fitting 11. A small annular groove 21 is formed in the exterior surface of the body 18 adjacent to and at the point of beginning of the flange 20 to form a seat or 50 place to retain the sanding disc 2 therein upon assembly of this disc and fitting for temporary unitary relationship thereof when disassembled from the remainder of the unit.

From the preceding description it is believed that it will be apparent that the head 4 will 55 threadedly receive the primary fitting 11 with the disc 3 seated in the groove 16, and that the primary fitting will threadedly receive the secondary fitting 19 with the disc 2 seated in the annular groove 21 therein and that these fittings and discs including the backing disc 8 will stand in nested position and relationship substantially as shown in Figure 6.

Ordinarily the upper disc 2 is coarse for fast cutting. After completion of roughing in the 60 work it becomes necessary to smooth the worked surface and free it of scoring caused by the coarser abrasive, to bring the disc 3 into play for fine sanding it is only necessary that each of the discs, that is discs 2 and 3 be grasped along 65 their periphery and with one hand holding the lower disc stationary, the other hand rotates the upper disc in a counter-direction to the running of the threads whereby the secondary fitting is threadedly disconnected from the primary fitting 70 whereupon the fine sanding disc or disc 3 in the 75

present order is uncovered for use. It is to be noted that the afore-described operation is at complete variance with current practice wherein it is necessary to employ wrenches to disconnect a single disc from the head 4 and thereafter obtain and by using wrenches again threadedly insert the desired sanding disc. It is this inconvenience of operation which causes many workmen to sluff and in many cases cause ruin of the part worked upon or to so nearly ruin the work that extensive re-working thereof is required.

In Figures 8-16 we show another form of structure adapted to effect easy and quick interchangeability of the sanding discs 2 and 3, which as shown in Figures 10 and 13 are also supported by a resilient backing disc 8, and wherein this latter disc and the sanding discs 2 and 3 are all held in releasable clamped position upon a rotating head 22 which is in general constructed in the form of its counter-part 4 as shown in Figures 1-8, that is, it is formed with a bore 23 having a lower threaded end for threaded union with the motor shaft 5 and with coarse or fast running threads 24 to receive the like threaded shank of the primary fitting 25, which fitting is also formed with a medially and longitudinally disposed bore 26 which differs from the bore 4a in fitting 11 in that it is not threaded, but is adapted to slidably receive the cylindrical body 27 of the secondary fitting 28.

Slots 29 are cut through the wall of the primary fitting 25 to receive and guide the free ends of a pin 30 which extend through elongated slots 27a formed in the body 27 of the part 28, and these slots have an upper curved side 31 whereby one end of the slot forms a pocket 29a wherein the pins are retained under spring pressure as will be subsequently pointed out, while the other end of these slots extend more or less vertically through the wall of the fitting to terminate in the annular recess 32 in the top thereof whereby the fitting 28 and the pins 30 associated therewith may be inserted into and withdrawn from the bore 26 for functional use assembly.

An annular flange 33 is formed upon the fitting 25 to provide a pressure surface for securely holding the backing disc 8 and the sanding disc 3 upon the head 22, while a small annular groove 34 in the under-surface of the flange is adapted to receive and detachably support the disc 3 therein against dislocation by minor force.

The secondary fitting 28 is provided with an annular flange 35 extending from the body thereof and this flange is also provided with an annular groove 28a upon its lower side to receive and support the sanding disc 2 against dislocation by minor force. The cylindrical body 27 of the fitting 28 is formed with a medial longitudinally extending bore 36 to receive a finger actuated depressable plunger 37 through which there extends the pin 30 aforementioned, and the cylindrical walls thereof are formed with the elongated slots 27a through which the pin 30 project for movement through the slot 29 in the primary fitting 25. The lower end of the bore 36 is closed as by the end wall 39, and a spring 38 is sealed under tension within the bore 36 with its one end pressing against the closure wall 39 and its other end pressing against the lower end of the plunger 37 whereby the plunger is normally held in an upper most position, which position is limited by the upper end of the slot 27a when dis-assembled from the unit as a whole, or

alternatively by the slot 29 when in assembled position within the primary fitting.

Figure 17 shows a modification of structure which is primarily concerned with lowering production costs, here the rotatable head 4 is formed with a bore 4b having smooth side walls 4c and the primary fitting 12 in lieu of the threads 10a is formed with smooth exterior walls 12a for socketing in the bore 4b. The lower end of the head 4 closely envelops the motor shaft 5 and the fitting 12 is centrally bored and internally threaded at 12b for screw threading upon the shaft 5 whereby when assembled as shown in the drawing these two structural elements are securely joined for holding the disc 8 and the disc 3 in functional use position and, the fitting 12 when thus positioned upon the motor shaft 5 is adapted to threadedly receive the secondary fitting 19 threadedly positioned therein so that with respect thereto, the final assembly of the several mechanical parts including the abrasive discs 2 and 3 and the backing disc 8 have in general the appearance of the assembly shown in Figures 1 and 2.

Assembly and dis-assembly of the primary and secondary fittings 25 and 28 with the discs 2, 3 and 8 is believed to be obvious from the preceding description, however, it may be stated that ordinarily the disc 3 remains in the assembly upon the fitting 25 until worn out whereupon this fitting is unscrewed from the head 22 by grasping the rim of the disc and rotating it counter to the running of the threads 24 whereupon a new disc is or may be installed in the manner aforesaid.

As previously stated the use of a power sander requires the alternate use of a fine sanding disc and a courser one as at 2 and 3. After using the courser disc 2 and if it is desired to use the fine disc 3 it is only necessary to depress and rotate the plunger 37 so that the pin is released from the pocket 29a for freeing the part 27 from within the slot 29 whereafter the secondary fitting 28 may be withdrawn from the primary fitting 25. To again use the disc 2 the secondary fitting is installed to use by a reversal of the afore-described dis-assembly thereof.

Having thus described our invention in its presently preferred form but without being specifically limited thereto, that which we believe to be patentably novel and for which we seek Letters Patent is as follows:

We claim:

1. The combination in a portable electric motor having a sanding disc support head secured to the shaft of the motor for rotation therewith, of means to detachably secure a plurality of sanding discs on said support head, said means comprising an arbor for each of the sanding discs on the support head, said arbors being formed with threads thereon and therein for threaded connection with one another and with a screw threaded motor shaft extending at least partially through said support head, said arbors being formed with flanges whereby upon nesting thereof within one another including said support head said flanges and said support head constitute pressure surfaces adapted to secure said sanding discs therebetween.

2. A motor driven rotatable head adapted and arranged to support a plurality of sanding discs thereon, said rotatable head being formed with a flange and having a bore extending inwardly medially therethrough, a primary and a secondary fitting, said primary fitting comprising a

flanged arbor having coarse internal threads and being formed with an annular groove adjacent said flange, said secondary fitting comprising a flanged arbor having coarse exterior threads and being formed with an annular groove adjacent 5 said flange, said primary fitting being adapted to be fitted in said rotatable head and the secondary fitting being adapted to be screw threaded into said primary fitting and the annular grooves in both of said fittings being adapted to retain a 10 sanding disc upon each thereof, the flange of said head and the flanges of the primary and secondary fittings constituting pressure surfaces adapted to compressively grip sanding discs in 15 said annular grooves for functional use retention.

ARTHUR TURTON.
HENRY ELBERT HICKMAN.
